NICHOLAS KRUEGER, OF EAST RUTHERFORD, NEW JERSEY, ASSIGNOR TO EAST RUTHERFORD SYRINGE CO., INC., OF EAST RUTHERFORD, NEW JERSEY, A CORPORATION OF NEW JERSEY

SYRINGE ATTACHMENT CLAMP

Application filed January 29, 1929. Serial No. 335,877.

The present invention relates to syringes of the hypodermic type and embodies, more particularly, an improved hypodermic syringe capable of use with needles and other tools having varying sized bases.

In practice, it is desirable in hypodermic work to use needles and other attachments of varying sizes for a given size of syringe and in existing constructions, no simple and effective devices are available for interchanging such attachments on the syringe. It is further desirable to maintain a definite relationship between the beveled side of the needle and the scale on the syringe barrel in order that the operator may watch the scale while operating the syringe.

It is accordingly an object of the invention to provide a syringe capable of receiving a plurality of needles or other tools of varying sizes, the tools being selectively applied to the syringe with equal facility.

A further object of the invention is to afford a means for locking the tool to the syringe in such manner that a predetermined relationship between portions of the tool and the syringe may be maintained when securing the tool to the barrel of the syringe.

The attainment of the above objects is accomplished by the provision of an adapter upon the barrel of the syringe which has a fitting to receive the base of the needles or other tools, the fitting being of such character that the needles and tools are fitted with equal degrees of nicety, regardless of their sizes. Cooperating with this fitting is a manually operable retaining member which holds the needle or tool in operative relation to the fitting.

Further objects of the invention, not specifically enumerated above, will appear as the detailed description thereof is considered and reference will now be had to the accompanying drawings, wherein:

Figure 1 is a plan view of an assembled syringe and needle, the latter being secured to the barrel of the syringe by a construction embodying the present invention.

Figure 2 is a segmental view in section, taken on line 2—2 of Figure 1, and looking in the direction of the arrows, this view show-

ing the specific manner in which the needle is secured to the barrel of the syringe.

Figure 3 is a view similar to Figure 2, showing the syringe carrying a catheter or curved nozzle.

Figure 4 is a perspective view showing the manually operable means for securing the needle or tool to the adapter.

Figure 5 is a perspective view showing the adapter which is carried by the syringe barrel, and upon which the needles or tools are secured. Incidentally, this view, taken with Figure 4, shows the adapter in the position which it assumes with respect to the retaining means when the latter is applied thereto during assembly.

Figure 6 is a view in side elevation of the adapter in loose position ready to receive a needle.

At the outset, it will be understood that the invention primarily embodies a connection for securing one element to another, although it has been illustrated as a means for securing a needle or other tool to the barrel of a syringe.

With a view to setting forth the invention specifically, reference will now be had particularly to Figures 1, 2, 4 and 5 wherein 10 designates the barrel of a syringe having a plunger 11 and a scale 12 for indicating a desired volume of fluid to be injected. At the end of the barrel opposite from the plunger, a barrel tip 13 may be formed, having an aperture 14 through which fluid may flow.

An adapter or coupling 15 having a recess 16 is fitted upon the barrel, the tip of the latter being snugly received in the recess 16. An axial passage 17 is formed in the adapter, preferably in alignment with the aperture 14 to afford an unobstructed path through which the fluid may flow. The adapter is generally barrel-shaped and has a tapered nozzle or male element 18. External threads 19 are formed on the adapter for a purpose to be described hereinafter.

A needle 20 having an opening 21 is formed with an axial passage and a base 22. The base is provided with a conical recess, or female member 23, within which the nozzle or male member 18 is received. An annular

bead 24 is formed on the needle base and cooperates with a retaining means to be described hereinafter, to secure the needle to the adapter.

5 Cooperating with the adapter to hold the needle, is a thimble or bushing 25, threaded internally at 26 to engage the threads 19, and knurled on its external periphery, as at 27, to facilitate manual operation. Coaxial with 10 the bushing is a semi-cylindrical extension 28 having an inwardly extending gripping flange 29. The extension and flange overlie the nozzle 18 as clearly shown in Figure 2. A coaxial apron 30 serves as a keeper and is 15 pressed or otherwise secured to the bushing. An inwardly extending rim 31 on the apron engages the threaded portion of the adapter to prevent the bushing from being entirely removed when unscrewed from the adapter.

20 In Figure 3 the needle is replaced by catheter or curved nozzle 32 having an end fitting 33 similar to the base of the needle 20. Obviously, the manner of securing this fitting to the nozzle is similar to that in which 25 the needle base is secured to the nozzle in the construction shown in Figures 1 and 2.

From the foregoing description it will be apparent that the adapter is snugly held on the barrel tip and carries the thimble or bushing with the gripping flange 29. To apply 30 a needle or other tool to the nozzle, the thimble 25 is advanced toward the end of the nozzle. When there is sufficient clearance between the gripping flange and the tapering 35 side of the nozzle to receive the bead 24 of the needle base or fitting 33, the needle or tool is slipped over the nozzle and the thimble backed up until the gripping flange 29 thereon engages the bead 24 and securely fits the 40 needle or tool upon the nozzle. The reverse operation is effected when the needle or tool is to be removed.

In applying the needle to the syringe, it will be apparent that it is but a simple matter 45 to hold the needle in any position desired, since it need only partake of axial movement during such operation. In this manner the needle is easily held so that its opening will be facing in the same direction as the scale 50 on the barrel of the syringe, thus enabling the instrument to be used more effectively.

From the description as outlined above, it will be apparent that the invention is not 55 restricted to the specific construction embodied herein, but may be utilized with couplings of many forms and it is not to be limited save as defined in the appended claims.

1. A syringe provided at one end of its barrel with a tip, an adapter for securing 60 a tool in rotatably adjusted position on the barrel, said adapter comprising a male member provided with external threads and formed with a recess at one end for receiving 65 the barrel tip and at its opposite end with a tapered nozzle adapted to be in-

serted into the socket recess of the base of a tool, a thimble internally threaded for engagement with the threads of the adapter and provided with a flange overlying the tapered nozzle for engaging the usual bead 70 on the base of the tool to draw the same axially into engagement with the nozzle, and an apron on the thimble having an inwardly extending flange to engage the threads on the adapter to limit the movement of the 75 thimble toward the nozzle.

2. A syringe provided at one end of its barrel with a tip, an adapter for securing a tool in rotatably adjusted position on the barrel, said adapter comprising a male member provided with external threads and formed with a recess at one end for receiving 80 the barrel tip and at its opposite end with a nozzle adapted to be inserted into the socket recess of the base of a tool, and a thimble internally threaded for engagement with the threads of the adapter and provided at one end with a flange for engaging the usual bead on the base of the tool to draw the same axially into engagement with 85 the nozzle and provided at the other end with a rim adapted to engage the threads on the adapter to prevent the thimble from being removed from the adapter.

3. In combination with a syringe barrel 90 and a tool having a recessed base and radially projecting retaining member to be applied to the barrel, an adapter for securing the tool to the barrel having means to engage the barrel, a nozzle formed on the 100 adapter to engage the recess in the base of the tool, a thimble formed with an element to engage the radially projecting retaining member on the base of the tool, threads formed on the thimble and adapter to mount 105 the former adjustably on the latter, an apron on the thimble at the end distant from the engaging element, and an inwardly extending flange on the apron to engage the threads on the adapter and limit the movement of 110 the thimble toward the nozzle.

4. In combination with a syringe barrel and a tool having a recessed base and radially projecting retaining member to be applied to the barrel, an adapter for securing 115 the tool to the barrel having means to engage the barrel, a nozzle formed on the adapter to engage the recess in the base of the tool, a thimble formed with an element to engage the radially projecting retaining 120 member on the base of the tool, means to mount the thimble movably on the adapter, a retaining element on the thimble at the end distant from the engaging element, and an inwardly extending member on the element 125 to engage the adapter and limit the movement of the former toward the nozzle of the adapter.

5. In combination with a syringe barrel and a tool having a recessed base and radially 130

projecting retaining member to be applied to the barrel, an adapter for securing the tool to the barrel having means to engage the barrel, a tapered nozzle formed on the adapter to engage the recess in the base of the tool, a 5 thimble formed with an element to engage the radially projecting retaining member on the base of the tool, threaded means for mounting the thimble shiftable axially on the 10 adapter with the engaging element of the thimble overlying the tapered nozzle of the adapter, whereby axial movement of the thimble with respect to the adapter will vary the clearance between the nozzle and the engaging element of the thimble, and means to prevent removal of the thimble from the 15 adapter.

6. In combination with a syringe barrel and a tool having a recessed base and radially 20 projecting retaining member to be applied to the barrel, an adapter for securing the tool to the barrel having means to engage the barrel, a tapered nozzle formed on the adapter to engage the recess in the base of the tool, a 25 thimble formed with an element to engage the radially projecting retaining member on the base of the tool, and means to mount the thimble movably on the adapter with the engaging element of the thimble overlying the 30 tapered nozzle of the adapter, said means comprising a threaded connection between the thimble and adapter whereby axial movement of the thimble with respect to the adapter will vary the clearance between the nozzle 35 and the engaging element of the thimble.

7. In combination with a syringe barrel and a tool having a recessed base and radially 40 projecting retaining member to be applied to the barrel, an adapter for securing the tool to the barrel having means to engage the barrel, a nozzle formed on the adapter to engage the recess in the base of the tool, a thimble formed with a gripping flange integral therewith to engage the radially projecting retaining 45 member on the base of the tool, threads formed on the thimble and adapter to mount the former adjustably on the latter thereby to vary the position of said element relative to said retaining member, and means for securing 50 the thimble permanently to the adapter.

8. In combination with a syringe barrel and a tool having a recessed base and radially 55 projecting retaining member to be applied to the barrel, an adapter for securing the tool to the barrel having means to engage the barrel, a nozzle formed on the adapter to engage the recess in the base of the tool, a thimble formed with an element to engage the radially 60 projecting retaining member on the base of the tool, means to mount the thimble on the adapter in longitudinally adjustable relation thereto thereby to locate said element in position to engage differently spaced retaining members.

65 9. In combination with a syringe barrel

and a tool having a base and a radially projected retaining member to be applied to the barrel, an adapter for securing the tool to the barrel having means to engage the barrel and means to engage the base of the tool, a 70 thimble formed with an element to engage the radially projecting retaining member on the base of the tool to shift the same axially, threaded means for mounting the thimble longitudinally movable on the adapter thereby to cause the adapter to secure in place different tools having variably positioned retaining members.

Signed at East Rutherford in the county of Bergen and State of New Jersey this 14th 80 day of January, A. D. 1929.
